Primary Examiner — Selina Sikder(74) *Attorney, Agent, or Firm* — The Small Patent Law Group LLC; Christopher R. Carroll(57) **CLAIM**

The ornamental design for an inverter direct current busbar, as shown and described.

DESCRIPTION

FIG. 1 is a perspective view of an inverter direct current busbar;

FIG. 2 is an elevational view of a first side of the inverter direct current busbar shown in FIG. 1;

FIG. 3 is an elevational view of a second side of the inverter direct current busbar shown in FIG. 1;

FIG. 4 is an elevational view of a third side of the inverter direct current busbar shown in FIG. 1;

FIG. 5 is an elevational view of a fourth side of the inverter direct current busbar shown in FIG. 1;

FIG. 6 is a plan view of a top of the inverter direct current busbar shown in FIG. 1; and,

FIG. 7 is a plan view of a bottom of the inverter direct current busbar shown in FIG. 1.

The broken lines depict portions of the inverter direct current busbar which form no part of the claimed design.
